(No Model.)

O. A. MOSES.

VOLTAIC ARC LAMP.

No. 276,705.

Patented May 1, 1883.

UNITED STATES PATENT OFFICE.

OTTO A. MOSES, OF NEW YORK, N. Y.

VOLTAIC-ARC LAMP.

SPECIFICATION forming part of Letters Patent No. 276,705, dated May 1, 1883.

Application filed October 26, 1882. (No model.)

To all whom it may concern:

Be it known that I, OTTO A. MOSES, of New York city, in the county and State of New York, have invented a certain new and useful Improvement in Voltaic-Arc Lamps, of which the following is a specification.

The object I have in view is to produce a simple and efficient regulating mechanism for arc-lamps, wherein the upper or positive carbon only is fed forward, which mechanism will act positively to lift the upper carbon in establishing the arc, and to force it downwardly when the arc is broken to complete the circuit, and will also permit of a uniform and steady gravity-feed of the upper carbon, controlled by the lengthening of the arc.

A further object is to produce convenient means for holding the lower carbon so that it can be readily brought into line with the upper carbon and held rigidly in position.

Constructions embodying the invention are shown in the accompanying drawings, in which Figure 1 is a vertical section of the principal operating parts of an arc-lamp; Fig. 2, a vertical section of a portion of the carbon-carrying tube and inclosed parts, showing a modified arrangement of the parts; Fig. 3, a top view of the assisting magnetic intensifier and clamp; Fig. 4, a sectional view of the regulating dash-pot, and Fig. 5 a vertical section and partial elevation of the device for holding and centering the lower carbon.

A is a solenoid or hollow electro-magnet, the coils of which are connected in series with the carbon electrodes B B' of the lamp, and which alone operates the regulating mechanism. The tube C, carrying the upper or positive carbon, B, passes through this solenoid or electro-magnet, and is guided therein. It is filled with glycerine or other suitable viscous liquid, D, and passes up within the supporting-tube E, rising from the head of A.

F is a rod supported by a spiral spring, G, which is secured to the tube E, and is connected adjustably with the rod F by a block, *a*, and set-screw *b*. The rod F carries the core or armature H of the solenoid or electro-magnet, such core or armature being sleeved or held loosely upon the rod.

Above H is secured rigidly to the rod F a

block, I, of magnetic or non-magnetic material, which block is beveled on its lower side next to the core or armature, one or more balls, K, preferably of non-magnetic metal, being located in the wedge-shaped space between the flat upper end of the core and beveled lower face of the block. The core or armature is held up in active position by a spring, c, and adjustable nut *d* on the lower end of rod F. The pressure of the spring c, while holding the balls K out against the tube C, maintaining electrical contact constantly therewith, is not sufficient to prevent such tube from dropping by gravity, its movement being retarded by the friction of the balls, as well as by the liquid within the tube, and the regulating dash-pot about to be described. When the circuit to the lamp is completed the core H will be drawn up with a quick forcible movement. This will jam the balls K out against the tube C, clamping the core to the tube. In this quick forcible movement the magnetic clamp formed by the balls might not be certain in its action. The viscous liquid D, however, by reason of the atmospheric pressure thereon and the limited passage-way through which it can flow around the core, causes the core and tube to move as one, and the tube is carried up with the core against the resilience of the spring G, separating the carbon electrodes and establishing the arc. The lengthening of the arc causes the core to diminish the pressure on the balls and to release the tube C, and also permits the spring G to act downwardly, and between these two actions the upper carbon is given a regular downward movement. If the arc, however, should be broken or be unduly lengthened by the sticking of the tube in its guides, the spring G would act to give the rod and core a quick and forcible downward movement, and the carbon-carrying tube would be carried with the core through the medium of the liquid.

To produce a uniform movement of the core or armature, the additional dash-pot S shown in Fig. 4 is employed. For this purpose the supporting-tube E is extended upwardly and provided with a cup, o, from the center of which is suspended a hollow cylindrical dash-pot plunger, p, open at its lower end and closed at

its upper end, with the exception of the small air-holes *q*. This plunger works in the cylindrical vessel *r*, partly filled with glycerine, *S*, or other suitable viscous liquid. The vessel *r* is attached to the upper end of the rod *F*, and the dash-pot thus makes uniform the movement of said rod, caused by the solenoid or electro-magnet and the spring *G*.

The parts thus far described form a complete and efficiently-operating regulating mechanism. They may be assisted, however, by a magnetic intensifier and clamp, *L*, external to the carbon-holding tube, composed of balls or rollers *e*, held by a ring, *f*, and having an independent movement thereon to a small extent. This magnetic clamping-ring surrounds the tube *C* below *A*, and is limited in its vertical movement by arms *g* or a suitable cage. In the arrangement shown in Fig. 1 the ring *e* of balls located below the core serves to lengthen such core and intensify the action of the solenoid or throw the magnetic center of the core down to a lower point. The balls are all attracted inwardly by the core clamping evenly upon the carbon-carrying tube, and, being attracted upwardly by the solenoid, they serve to assist in raising the carbon-carrying tube, forming an external magnetic clamp, acting in conjunction with the internal magnetic clamp formed by the balls *K*. This divided magnetic clamping-ring may be used with the arrangement shown in Fig. 2, in which the balls *K* are brought down to a point opposite the ring, the internal and external clamps acting upon the carbon-holding tube opposite each other. To do this the block *M*, corresponding to *I*, is extended downwardly, and is made magnetic, so as to form a part of the core or armature, the movable part *N* of the core or armature being made shorter than in Fig. 1. With this arrangement it is desirable that the core should extend above the solenoid the same distance that it extends below such solenoid.

To hold and center the lower carbon, *B'*, I provide a socket, *O*, having a clamp to hold the carbon, which is preferably a ring, *h*, turning upon the split end *i* of the socket. This socket has a disk, *P*, provided with a concave lower side, *k*, and a screw-shank, *l*, extending downwardly from the center at this disk. The shank *l* passes through an opening, *m*, in the lower cross-piece, *Q*, of the lamp-frame, the opening *m* being large enough to permit the shank to be moved laterally a limited extent in any direction. A disk, *R*, having a concave upper side, *n*, screws onto the lower end of the shank *l*, and impinges against the lower side of the cross-piece *Q*. The concave faces of the disks assure the rigid holding of the parts, while the opening *m* allows the lower carbon to be brought into line with the upper carbon.

What I claim is—

65 1. In regulators for arc-lamps, the combina-

tion, with the solenoid or electro-magnet, of the carbon-carrying tube, the core or armature within such tube, and a clamp operated by the movement of such core or armature and acting upon the interior of said tube, substantially as set forth. 70

2. In regulators for arc-lamps, the combination, with the solenoid or electro-magnet, of the carbon-carrying tube, the liquid within such tube, the core or armature also within such tube, and a clamp operated by the movement of such core or armature and acting upon the interior of said tube, substantially as set forth. 75

3. In regulators for arc-lamps, the combination, with the solenoid or electro-magnet, of the carbon-carrying tube, the spring-rod, the core or armature movable upon such rod, and a clamp operated by the movement of the core or armature on the rod, substantially as set forth. 80

4. In regulators for arc-lamps, the combination, with the solenoid or electro-magnet, of the carbon-carrying tube, the spring-rod, the beveled block secured to such rod, the core or armature movable upon the rod, and the clamp-balls, substantially as set forth. 85

5. In regulators for arc-lamps, the combination, with the carbon-carrying tube and spring-rod, of the beveled block secured to such rod, the core or armature movable upon such rod, the clamping-balls, and the spring and adjusting-nut, substantially as set forth. 95

6. In regulators for arc-lamps, the combination, with the solenoid or electro-magnet, of the carbon-carrying tube, the core or armature within such tube, the magnetic clamp within the tube, and the dash-pot regulating the movement of the core or armature, substantially as set forth. 100

7. In regulators for arc-lamps, the combination, with the solenoid or electro-magnet, of the carbon-carrying tube, the liquid within such tube, the core or armature also within such tube, the magnetic clamp also within such tube, the spring forcing the core or armature downwardly, and the dash-pot regulating the movement of the core or armature, substantially as set forth. 105

8. In regulators for arc-lamps, the combination, with the solenoid or electro-magnet, of the carbon-carrying tube, the spring-rod within such tube, the core or armature mounted loosely on said rod, the clamp operated by the movement of the core or armature on the rod, and the dash-pot connected with such rod, substantially as set forth. 115

9. In regulators for arc-lamps, the combination, with the carbon-carrying tube and the magnetic clamp within the same, of the external magnetic clamp, substantially as set forth. 125

10. In regulators for arc-lamps, the combination, with the carbon-carrying tube, of the clamping-balls within the same and the external divided magnetic clamping-ring, substantially as set forth. 130

11. In arc-lamps, the combination, with the frame having opening, of the socket for the lower carbon provided with a clamping device for securing the carbon therein, the shank or bolt smaller than the frame-opening, and the concave disks securing the carbon-socket to the frame independent of the device for holding the carbon in such socket, substantially as set forth.

This specification signed and witnessed this 10
11th day of October, 1882.

OTTO A. MOSES.
